UNITED STATES PATENT OFFICE.

OTTO DAVIS, OF BURLINGTON, IOWA.

DESIGN FOR A BUTTON.

SPECIFICATION forming part of Design No. 35,491, dated December 31, 1901.

Application filed December 2, 1901. Serial No. 84,485. Term of patent 3½ years.

To all whom it may concern:

Be it known that I, OTTO DAVIS, a citizen of the United States, residing at Burlington, in the county of Des Moines and State of Iowa, **5** have invented and produced a new and original Design for Buttons, of which the following is a specification, reference being had to the accompanying drawings, forming part thereof.

10 Figure 1 is a view of the front of a button, showing my new design. Fig. 2 is a view of the back of a button, showing my new design thereon; and Fig. 3 is a side view of the button.

15 As shown in the drawings, the leading or material feature of my design comprises a button composed of two disks of different diameters connected centrally by a stud, the

smaller disk having on its outer face the representation of a man, while the larger disk **20** has on its outer face a representation of an exposition-building, both representations being inclosed within a fluted border.

Having described my invention, what I claim as new, and desire to secure by Letters **25** Patent, is—

The design for a button, as herein shown and described.

In testimony whereof I have signed my name to this specification in the presence of **30** two subscribing witnesses.

OTTO DAVIS.
